UNITED STATES PATENT OFFICE.

MATT L. WOLFE, OF MIAMISBURG, OHIO.

COOLING APPARATUS.

No. 815,773.

Specification of Letters Patent.

Patented March 20, 1906.

Application filed August 26, 1905. Serial No. 275,965.

To all whom it may concern:

Be it known that I, MATT L. WOLFE, a citizen of the United States, residing at Miamisburg, in the county of Montgomery and State of Ohio, have invented certain new and useful Improvements in Cooling Apparatus; and I do hereby declare the following to be a full, clear, and exact description of the invention, such as will enable others skilled in the art to which it appertains to make and use the same.

This invention relates to apparatus for cooling wheel-tires and other similar articles; and it consists in the novel construction and combination of the parts hereinafter fully described and claimed.

In the drawings, Figure 1 is a cross-section through the cooling apparatus. Fig. 2 is a plan view of the cooling apparatus.

A is a tank or vessel for holding water, which is preferably circular. B represents inclined tracks arranged in a circle inside the said tank. These tracks are preferably formed of a continuous round bar of metal bent to the required form. The tracks may be inclined to the right or to the left, as preferred; but all the tracks of one apparatus must be inclined in the same direction. These tracks have horizontal portions 3 at their upper ends, horizontal portions 4 at their lower ends, feet 5, which rest on the tank-bottom and which support the parts 4 at a short distance above the tank-bottom, and vertical portions 6, which connect the said parts 3 with the said feet. The parts 5 and 6 also form stops against which the lower end portions of the loops strike. These stops prevent the platform from being moved too far in each direction. If no stops were provided and the platform were moved too far in one direction or if it were moved in the wrong direction, the rollers would run off the parts 3 and would drop suddenly and with violence upon the parts 5.

C is a support or platform, preferably formed of bars of wood or iron suitably jointed together. D represents loop-shaped brackets secured to the under side of the said platform and extending under the said tracks. Rollers d are journaled on pins e in the loops of these brackets and are arranged to run upon the inclined tracks B. The tracks are inclined at any approved angle which will best support the platform, and the platform is raised and lowered in the tank by moving it in a circular direction. The heated tire or other object is placed on the platform when the latter is raised, and the platform is then turned so as to lower it below the surface of the water.

What I claim is—

1. In cooling apparatus, the combination, with a tank, of inclined tracks formed of bars provided with stops and supported above the bottom of the said tank, a platform, loop-shaped brackets secured to the said platform and passing under the said bars, and engaging with the said stops and rollers, journaled in the said brackets and resting on the said bars.

2. In cooling apparatus, the combination, with a tank, of inclined tracks formed of bars having stops and horizontal portions at their ends and feet which rest on the tank bottom and support the said horizontal portions above the tank bottom, a platform, loop-shaped brackets secured to the said platform and passing under the said bars, and engaging with the said stops and rollers journaled in the said brackets and resting on the said bars.

In testimony whereof I have affixed my signature in the presence of two witnesses.

MATT L. WOLFE.
